UNITED STATES PATENT OFFICE

118,860

DESIGN FOR A GLIDER OR THE LIKE

Zack S. Logan, Louisville, Ky., assignor to Logan Co. Inc., Louisville, Ky., a corporation of Kentucky

Application November 16, 1939, Serial No. 88,325

Term of patent 7 years

To all whom it may concern:

Be it known that I, Zack S. Logan, a citizen of the United States, residing at Louisville, in the county of Jefferson and State of Kentucky, have invented a new, original, and ornamental Design for Gliders or the like, of which the following is a specification, reference being had to the accompanying drawing, forming a part thereof.

Figure 1 is a front perspective view of a glider showing my new design,

Figure 2 is a side elevational view of one of the glider ends, and

Figure 3 is an end elevational view of the same.

The characteristic feature of my design resides in the portion shown in solid lines.

I claim:

The ornamental design for a glider or the like, as shown and described.

ZACK S. LOGAN.
